ABRADING MACHINE

Filed July 16, 1927

UNITED STATES PATENT OFFICE

ARVID BJORKLUND, OF MINNEAPOLIS, MINNESOTA

ABRADING MACHINE

Application filed July 16, 1927. Serial No. 206,317.

My present invention relates to an improved abrading machine and more particularly to a sander for finishing certain kinds of work, such as patterns, that cannot be finished on the customary disk sander, and has for its object to provide such a machine that is self-contained, portable, extremely simple, with few parts to get out of order and that are very accessible, and highly efficient in its action.

To the above end, generally stated, the invention consists of the novel devices and combinations of devices hereinafter described and defined in the claims.

15 In the accompanying drawings, which illustrate the invention, like characters indicate like parts throughout the several views.

Referring to the drawings:

20 Fig. 1 is a perspective view of the invention;

Fig. 2 is a view partly in side elevation and partly in central vertical section with some parts broken away;

25 Fig. 3 is a fragmentary view with some parts sectioned on the line 3—3 of Fig. 2 with the table shown in a tilted position by means of broken lines;

Fig. 4 is a fragmentary detail view in section taken on the line 4—4 of Fig. 2, on an enlarged scale;

Fig. 5 is a detail view in section taken on the line 5—5 of Fig. 2, on an enlarged scale;

35 Fig. 6 is a view principally in section taken on the line 6—6 of Fig. 2, on an enlarged scale; and Fig. 7 is a perspective view of the adapter.

The numeral 8 indicates a base removably supported on four legs 9 cast in pairs, and to which legs the base is rigidly secured by screws. The pairs of legs 9 are rigidly but detachably connected by a pair of transverse tie rods 10. Cast with the base 8, at the center thereof, is a case 11 which extends both below and above said base. In the bottom of the case 11 is a drain hole normally closed by a screw plug 12. Formed with the case 11, at the top thereof, is an inturned flange 13 having a rabbeted seat 14 on which

is removably mounted a cover 15 for said case.

Overlying the case 11 is a round table 16 having a flat smooth work-supporting surface and suitably reinforced by ribs formed with the under side thereof. On the under side of the table 16 is a pair of diametrically opposite hinge lugs 17 having open notch-like seats 18 which straddle a pair of axially aligned pivot pins 19 rigidly secured in bearing brackets 20 formed with the flange 13. These pivot pins 19 extend inward from the bearing brackets 20 and the lugs 17 snugly fit between said brackets and thus hold the table 16 against edgewise movement longitudinally of the pivot pins 19 but with freedom for tilting movement about the axes of said pins.

Screws 21, having threaded engagement with the lower ends of the bearing lugs 17, prevent the table 16 from being lifted from said pivot pins 19. To remove the table 16 from the pivot pins 19 it is only necessary to remove the screws 21. To releasably but rigidly hold the table 16 in a horizontal position or different tilted positions, the same is provided with a quadrant 22 having a circumferentially extended slot 23, the center of which is at the axes of the pivot pins 19. A set screw 24 extends through the slot 23, has shouldered engagement with the quadrant 22 and screw-threaded engagement with one of the bearing brackets 20. To positively position and further hold the table 16 in a true horizontal position there is provided a pin 25 adapted to be inserted through aligned bores in depending ear 26 on the quadrant 22 and in the case 11.

A short chain 27 secures the pin 25 to the respective bearing bracket 20 to prevent the same from being lost. Formed in the top of the table 16, at the center thereof, is a large round opening 28, and the table, at its opening 28, is rabbed to afford a seat 29 in which is removably supported a disk-like adapter 30 having a relatively long slot 31 at its center that extends transversely of the projected axes of the pivot pins 19.

Integrally formed with the under side of the cover 15 is a pair of depending ways

32 that extend nearly to the bottom of the case 11. A crosshead 33 is mounted in the ways 32 for vertical reciprocatory movement and supports an upright shaft 34 for reciprocating movements therewith. The lower end of the shaft 34 rests on a bearing lug 35 integrally formed with the crosshead 33 and has a depending reduced trunnion 36 journaled in said bearing.

10 To the lower end portion of the trunnion 36 is applied a nut 37 to prevent the shaft 34 from being endwise lifted from the bearing lug 35. The intermediate portion of the shaft 34 is journaled in a removable bearing 38 mounted in a hub-like depending flange 39 formed with the cover 15 and keyed thereto against rotation. The shaft 35 terminates below the table 16, has a tool-holding socket 40 formed therein, and a grooved 15 wheel 41 is keyed to said shaft above the bearing 38.

20 Rotary motion is imparted to the shaft 34, from an electric motor 42, by a round belt 43 which runs over the grooved wheel 41 and a grooved wheel 44 on the armature shaft of said motor. The motor 42 is turned on its side with its armature shaft parallel with the shaft 34, and its base 45 is bolted to the vertical member of an L-shaped bracket 46 supported on an extension 47 integrally formed with the base 8 and detachably secured thereto by a nut-equipped bolt 48 which extends through a longitudinally extended slot 49 in said 25 bracket and a bore in the base extension 47. Obviously, by adjusting the bracket 46 toward or from the case 11, the belt 43 may be placed under the proper tension. The electric motor 42 is provided with a switch 50 30 which extends above the base 8 and case 11 where it is out of the way and at the same time easy to operate. A guard 51 for the belt 43 and wheel 44 is detachably secured to the vertical member of the bracket 46 35 and extends to the table 16.

40 Reciprocatory movement is imparted to the crosshead 33 from the shaft 34 by a worm 52 formed with said shaft and meshes with a worm gear 53 journaled at 54 to said crosshead and has on one of its faces a crank pin 55 to which the lower end of a link 56 is pivoted. The upper end of this link 56 is pivoted to a pair of ears 57 formed with the cover 15 on the under side thereof. Obviously, under the rotation of the shaft 34 45 the crosshead 33 will be reciprocated at a much reduced speed over that of the rotation of said shaft due to the ratio between said worm 52 and worm gear 53.

50 A spindle 58 is removably applied to the upper end of the shaft 34 and is axially aligned therewith. On the lower end of this spindle 58 is a reduced shank 59 that fits in the socket 40 and is held by a set 55 screw 60 for rotation with said shaft. The

spindle 58 projects through the slot 31 in the adapter 30 and materially above the table 16.

5 A piece of sand paper α is applied around the spindle 58 and its longitudinal edge portions are fitted into a longitudinally extended slot 61 formed in said spindle to hold the sand paper in position. A piece of work γ is positioned on the table 16 to be sanded by the spindle. By tilting the table 75 16 the work γ can be positioned at any desired angle in respect to the axis of the spindle 58.

10 Within the case 11 is a body of oil α in which the crosshead 33 and parts carried thereby work. It will be noted that the level of oil is substantially at the upper end 80 of the crosshead 33 when in its lowermost position so that said crosshead will pick up sufficient oil during its upward stroke to lubricate the ways 32 and the shaft 34 will keep its bearing 38 lubricated. It will also be noted that the trunnion 36, worm 52, worm gear 53 and the crank connection 55 with the link will run substantially all of 85 the time in the body of oil α . There will be sufficient splash to keep the upper bearing for the link 56 lubricated. With the parts thus lubricated, the life thereof will be materially lengthened and the machine 90 will operate with very little noise.

15 Obviously, by loosening the screw 60 the spindle 58 may be removed from the shaft 34, and as previously stated, by removing the screws 21 the table 16 may be lifted 105 from the bearing brackets 20. After the table 16 is removed from the machine, the cover 15 may be removed from the case and all of the parts carried thereby.

20 The cover 15 is rigidly but detachably secured in its seat 14 by a plurality of screws.

25 What I claim is:

1. In a machine of the kind described, the combination with a case, a removable cover for the case, an upright shaft journaled in the cover, means for driving the shaft, means carried by the cover within the case for reciprocating the shaft, a table overlying the case, and a tool holder applied to 110 the shaft to partake of its rotary and reciprocatory movements and extending through an aperture in the table.

2. In a machine of the kind described, a case having a displaceable cover, said cover having ways extending into the case, a crosshead on the ways, an upright shaft journaled on the crosshead and cover and having a tool holder, means for driving the shaft, a crank on the crosshead, a link connecting the crank to the case, and means for operating the crank from the shaft.

3. In a machine of the kind described, a reciprocatory cross-head, a rotatable shaft journaled on the cross-head and held there-

by for axial movement therewith, a relatively fixed bearing in which the shaft is journaled for endwise sliding movement under the reciprocatory movement of the cross-head, means for rotating the shaft, and means operated by the shaft and having a relatively fixed base of resistance for reciprocating the cross-head and shaft.

4. In a machine of the kind described, a reciprocatory cross-head, a rotatable shaft journaled on the cross-head and held thereby for axial movement therewith, a relatively fixed bearing in which the shaft is journaled for endwise sliding movement under the reciprocatory movement of the cross-head, means for rotating the shaft, a crank on the cross-head, an anchored link attached to the crank, and means for operating the crank from the shaft at a point between its journal on the cross-head and the bearing for reciprocating the cross-head and shaft.

5. In a machine of the kind described, a reciprocatory cross-head, a rotatable shaft journaled on the cross-head and held thereby for axial movement therewith, a relatively fixed bearing in which the shaft is journaled for endwise sliding movement under the reciprocatory movement of the cross-head, means for rotating the shaft, a worm on the shaft between its journal on the cross-head and the bearing on the support, a worm gear journaled on the cross-head and meshing with the worm, and an anchored link crank-connected to the worm gear.

6. The structure defined in claim 1 in which the case contains a body of oil in which the means reciprocated by the shaft works.

40 In testimony whereof I affix my signature.

ARVID BJORKLUND.
